UNITED STATES PATENT OFFICE

145,508

DESIGN FOR A RADIO RECEIVER

Paul Brinkman, Los Angeles, Calif.

Application October 3, 1945, Serial No. 122,507

Term of patent 14 years

(Cl. D56—4)

To all whom it may concern:

Be it known that I, Paul Brinkman, a citizen of the United States, residing at Los Angeles, in the county of Los Angeles, in the State of California, have invented a new, original, and ornamental Design for Radio Receivers, of which the following is a specification, reference being had to the accompanying drawing, forming part thereof, and wherein:

Fig. 1 is a plan view of a radio receiver embodying my new design;

Fig. 2 is a side elevational view of the said radio receiver; and

Fig. 3 is an end elevational view of the said radio receiver.

I claim:

The ornamental design for a radio receiver, as shown.

PAUL BRINKMAN.
